United States Patent Office

Des. 191,370
Patented Sept. 19, 1961

191,370

CIGARETTE LIGHTER

Stanley H. Newman, 19 E. 70th St., New York, N.Y.

Filed June 1, 1959, Ser. No. 56,172

Term of patent 14 years

(Cl. D48—27)

Fig. 1

Fig. 3

Fig. 2

Fig. 4

FIG. 1 is a front elevational view of a cigarette lighter, showing my new design;

FIG. 2 is a top plan view thereof;

FIG. 3 is an elevational view thereof as seen from the left of FIG. 1; and

FIG. 4 is a perspective view thereof.

The side of the cigarette lighter not shown is the same in appearance as the side shown.

I claim:

The ornamental design for a cigarette lighter, as shown and described.
